CLAIM

We claim the ornamental design for a bottle, as shown and described.

DESCRIPTION

FIG. 1 is a top, rear, and left side perspective view of a bottle showing our new design;

FIG. 2 is a front elevational view thereof;

FIG. 3 is a right side elevational view thereof; and,

FIG. 4 is a top plan view thereof.

The broken lines in the drawing views are for the purpose of illustrating environmental structure and form no part of the claimed design.
